UNITED STATES PATENT OFFICE.

LEVI FERGUSON, OF LOWELL, MASSACHUSETTS.

IMPROVEMENT IN PICKERS FOR FIBROUS MATERIAL.

Specification forming part of Letters Patent No. 57,109, dated August 14, 1866.

To all whom it may concern:

Be it known that I, LEVI FERGUSON, of Lowell, in the county of Middlesex and State of Massachusetts, have invented a new and Improved Picker for Fibrous Materials; and I do hereby declare that the following is a full, clear, and exact description thereof, which will enable others skilled in the art to make and use the same, reference being had to the accompanying drawings, forming a part of this specification, in which—

Figure 1 represents a longitudinal vertical section of this invention. Fig. 2 is a sectional plan or top view of the same.

Similar letters of reference indicate like parts.

This invention relates to a picker for rags, waste wool, or other fibrous materials, which is composed of a revolving picker-cylinder and a series of comb-plates, by the combined action of which the picking operation is effected.

The invention consists in the arrangement of comb-plates with their arms moving in slots in the frame, and cam-grooves with a segmental apron operating with a picker-cylinder having obliquely-set teeth on its face, whereby the operation of picking is greatly facilitated, as will be hereinafter more fully described.

A represents a picker-cylinder, which is mounted on an axle, B, having forwardly-projecting obliquely-set teeth on its face, and to which a rapid revolving motion is imparted in the direction of the arrow marked on it in Fig. 1 by a suitable power or motor of any desired description.

The material to be picked is fed to the cylinder A by means of feed-rollers C, which may be corrugated or fluted or otherwise arranged in the usual manner.

On being caught by the teeth of the cylinder the fibrous material is carried down over the segmental apron D, which is perforated to admit the teeth of the comb-plates E. These plates are supported by brackets a, from which suitable arms extend through slots b, in the frame of the machine, into suitable cam-grooves c, which are so shaped that they impart to said plates a motion toward and from the cylinder, and when two or more comb-

plates are used, which will be generally the case, said plates are moved at different periods, so that one is in when the other is out, and vice versa.

As the comb-plates pass in toward the cylinder their teeth take off the fibers from the teeth of the revolving cylinder, and as the comb-plates recede, their teeth being drawn back through the holes in the segmental apron D, clean themselves, so that the same are always in the proper condition to act, and the operation of picking is effected with ease and facility.

The teeth of the comb-plates are not liable to clog up, and the picker can be used with advantage for operating on textile or fibrous materials of any desired description—such as rags, waste wool, &c.

The cams c, which produce the reciprocating motion of the comb-plates, are mounted on shafts e f g, which are geared together by cog-wheels, and to which motion is imparted from the cylinder-shaft B, to the end of which is secured a pulley, i, from which a belt, j, extends over a pulley, k. This pulley is mounted on a shaft, l, from which the motion is transmitted to the first cam-shaft, e, by a pinion and cog-wheel; or the driving-power may be applied to the shaft l and transmitted to the remaining shafts by suitable belts, pulleys, and cog-wheels, which are so proportioned that the speed of the cylinder-shaft is much greater than that of the cam-shafts, and that the reciprocating motion of the comb-plates is quite slow.

I do not wish to confine myself, however, to any particular mechanism, but reserve the right to impart the requisite motion to the comb-plates by any suitable means.

What I claim as new, and desire to secure by Letters Patent, is—

The arrangement of the comb-plates E, with their arms moving in slots b of the frame, the cam-grooves c, and the segmental apron D, operating with the picker-cylinder A, all constructed in the manner and for the purpose herein specified.

LEVI FERGUSON.
